R. D. BRADEN.
ACETYLENE GENERATOR.
APPLICATION FILED FEB. 7, 1916.

1,270,258.

Patented June 25, 1918.

UNITED STATES PATENT OFFICE.

ROBERT D. BRADEN, OF CHICAGO, ILLINOIS, ASSIGNOR TO OXWELD ACETYLENE COMPANY, OF CHICAGO, ILLINOIS, A CORPORATION OF WEST VIRGINIA.

ACETYLENE-GENERATOR.

1,270,258.

Specification of Letters Patent. Patented June 25, 1918.

Application filed February 7, 1916. Serial No. 76,563.

To all whom it may concern:

Be it known that I, ROBERT D. BRADEN, a citizen of the United States, residing at Chicago, in the county of Cook and State of Illinois, have invented certain new and useful Improvements in Acetylene-Generators, of which the following is a specification.

This invention relates to the art of machines for generating acetylene gas, and has reference more particularly to a novel mechanism for releasing a reserve charge of carbide after the main body of the carbide in the hopper or holder has been used up and the supply of carbide in the machine exhausted except for the reserve charge, in order that the machine may not be kept out of operation any longer than is necessary to effect the recharging of the carbide hopper or holder. The invention is chiefly useful when employed in association with a signal device for automatically notifying the attendant of the machine when the carbide hopper requires recharging; and a practical form of visual signal device that is thrown to indicating position simultaneously with the emptying of the reserve charge holder is shown and described herein.

The general object of the invention is to increase the efficiency and serviceability of acetylene generators by obviating the necessity of guess-work on the part of the attendant as to when the machine needs recharging, avoiding unnecessary delays in effecting the recharging, and reducing the time period during which the machine is idle while undergoing recharging.

One practical means whereby the purposes and objects of the invention may be carried out is illustrated in the accompanying drawing, in which—

Figure 1 is a vertical axial section of a generator equipped with my present improvements;

Fig. 2 is a similar view of the upper portion of the generator taken in a plane at right angles to that of Fig. 1;

Fig. 3 is a fragmentary horizontal section on the line 3—3 of Fig. 2;

Fig. 4 is a fragmentary side elevation as viewed on the line 4—4 of Fig. 2;

Fig. 5 is a detail horizontal section taken on the line 5—5 of Fig. 4;

Fig. 6 is a fragmentary detail view in vertical section through the reserve charge-holder showing the latter in released or delivery position.

I have herein shown my present improvements as applied to a type of generator commonly known as an "outdoor" generator, the base and walls of which are insulated to protect the machine from the effects of freezing weather, but it will be understood that the improvements may be applied to any other type of generator that employs a movable member that is subject to variations in the gas pressure within the generator. Briefly describing the principal parts of the generator, 10 designates the outer casing, the same including a removable lid or cover 11; 12 designates the generation chamber; 13 the carbide hopper supported by and maintained within a stationary cylindrical member 14 which, in coöperation with the inner wall of the casing 10, forms an annular sealing chamber 15 within which operates the lower end of a vertically movable gas bell 16. The throat of the hopper 13 is controlled by a valve 17, the stem 17' of which extends upwardly through the top wall of the hopper and is normally urged upwardly by a light coil spring 17". 18 designates an abutment screw mounted on the top of the bell 16 that, on the descent of the latter, contacts with the upper end of the valve stem and opens the valve to admit a fresh charge of carbide from the hopper into the generation chamber. 19 designates a tube which conducts the gas from the generation chamber 12 into the gas bell 16, and 20 designates a filter on the upper end of a gas delivery pipe 21.

Referring now more particularly to the signal mechanism, 22 designates a shaft journaled in the side wall of the casing 10 near its upper end, on the outer end of which shaft is a semaphore 23 that is shiftable between the horizontal and vertical positions illustrated by dotted and full lines respectively in Fig. 4, its movements being preferably limited by stop pins 24 and 25. On the inner face of the semaphore 23 is a spring catch 26 that, when the semaphore arm is swung to vertical position, automatically engages and locks with a pin or stud 27 in the casing wall 10. On the inner end of the shaft 22 is a short arm 28 that is connected by a chain or cord 29 with the top of the gas bell 16. This chain 29 is of such length that the rise and fall of the bell in its normal working do not actuate the shaft 22. When, however, the carbide in the hopper is exhausted, the gas pressure within the bell 16 drops to such an extent that the bell falls to

an abnormally low position and thereby, through the chain 29, arm 28 and shaft 22, throws the semaphore arm 23 from horizontal to vertical position, this latter position of the semaphore arm indicating to the attendant an empty condition of the carbid hopper.

In order to prevent the machine from lying idle any longer than is necessary to effect recharging of the hopper (which might occur where the signal was not observed by the attendant until some time after it had been actuated to a position indicating the necessity of recharging), I provide a reserve charge-holder, and means for releasing the reserve charge that is also actuated by the bell, or equivalent device, on the same abnormal descending movement thereof, that actuates the signal device, so that after the main body of the carbid has been exhausted and this condition made known to the attendant by the indicator, the generation chamber may be supplied with another charge of carbid sufficient to maintain the gas pressure and keep the lights burning until the attendant has noted the condition of the machine and is ready to recharge the same. This reserve charge-holder and its actuating mechanism as herein illustrated comprises the following parts: 30 designates a horizontal shaft that is journaled in the tapered wall of the hopper 13 and extends across one side of the latter, and 31 is a plate fast on said shaft. The major portion of the plate overhangs the shaft toward the center of the hopper, while its rear or outer portion is counterweighted as shown at 32 so as to normally maintain the plate when empty in a horizontal position. Fast on the shaft 30 at one side of the plate is a disk 33 (Fig. 6) provided on its periphery with a radial shoulder 34, with which latter co-operates a pivoted pawl 35 that maintains the plate 31, when loaded with carbid, in raised or horizontal position. To the outer end of the pawl 35 is connected by a pin and slot joint 36 a rod 37 that extends upwardly through the top wall of the hopper and is adapted to be engaged at its upper end and depressed by the top wall of the bell when the latter descends to a position wherein it actuates the signal device. The rod 37 is normally maintained in elevated position and the pawl 35 in engagement with the shoulder 34 of the disk 33 by a coil spring 38 embracing the pivot shaft 39 of the pawl 35 and connected at one end to said shaft and at its other end to the pawl (Fig. 3).

When the carbid hopper is freshly charged a portion of the carbid is deposited on the plate 31; and as the carbid is gradually consumed and descends through the hopper, a reserve charge remains on the

plate 31, as indicated in Fig. 2, even after all the rest of the carbid has been delivered to the generation chamber. As the bell 16 descends to its abnormally low position wherein it actuates the indicator device, as above described, it also at the same time depresses the rod 37, withdraws the pawl 35, and thus permits the reserve charge-holder to tip under the load of carbid thereon to the delivery position indicated in Fig. 6, thereby furnishing the generation chamber with sufficient carbid to maintain the normal generation of gas for a considerable period after the indicator has been operated. As soon as the reserve charge of carbid has passed off the holder 31, the latter swings back to normal horizontal position under the influence of the counterweight 32 and the pawl 35 at once locks the same in such position and elevates the rod 37 under the influence of spring 38 as soon as the gas pressure has again raised the bell 16. By the expression "abnormal downward movement" as used herein, is intended a downward movement in excess of that occurring during the normal operation of the machine and such as is sufficient to actuate the indicator device.

It is believed that the foregoing description in connection with the illustration will make clear to those skilled in the art the structural features, mode of operation, and advantages of my present invention; and hence, I do not limit the invention to the particular embodiment herein shown and described but reserve to myself all such variations and modifications as fairly fall within the spirit and purview of the appended claims.

I claim:

1. The combination with an acetylene generator having a gas bell, of a pivoted holder mounted in the carbid hopper of the generator and adapted to retain a reserve portion of the carbid charged into the hopper after the main body of the carbid has been fed to the generation chamber, a shouldered disk rigid with said holder, a pawl normally engaging the shoulder of said disk to thereby lock said holder in carbid-receiving position, and means actuated by the gas bell under an abnormal downward movement thereof for dislodging said pawl from the shoulder of said disk, whereby to permit said holder to tilt to dumping position.

2. The combination with an acetylene generator having a gas bell, of a pivoted holder mounted in the carbid hopper of the generator and adapted to retain a reserve portion of the carbid charged into the hopper after the main body of the carbid has been fed to the generation chamber, a peripherally shouldered disk rigid with said holder, a detent pawl riding on the periphery of said

- disk and normally engaging the shoulder thereof to thereby lock said holder in carbid-receiving position, a spring normally pressing said pawl on the periphery of said disk, 5 and means actuated by the gas bell under an abnormal downward movement thereof for dislodging said pawl from the shoulder of said disk, whereby to permit said holder to tilt to dumping position.
- 10 3. The combination with an acetylene generator having a gas bell, of a pivoted holder mounted in the carbid hopper of the generator and adapted to retain a reserve portion of the carbid charged into the hopper after the main body of the carbid has been fed 15 to the generation chamber, a peripherally shouldered disk rigid with said holder, a detent pawl pivoted intermediate its ends and having its nose normally engaging the shoulder of said disk to thereby lock said 20 holder in carbid-receiving position, a push-rod connected to the heel of said pawl and adapted to be depressed by the gas bell to retract said pawl from locking engagement with said disk, and a spring urging said 25 push-rod upwardly and said pawl into engagement with the periphery of said disk.

ROBT. D. BRADEN.
